T. BURLEY

FIREPLACE HEATING SYSTEM

Filed Feb. 28, 1928

Inventor
Thomas Burley

John W. Maupin
Attorney

UNITED STATES PATENT OFFICE.

THOMAS BURLEY, OF SEATTLE, WASHINGTON.

FIREPLACE HEATING SYSTEM.

Application filed February 28, 1928. Serial No. 257,575.

My invention relates to fireplace heating systems and is an improvement over my prior Patent Number 1,638,286, issued August 9, 1927, for "fireplaces". The primary objects of my present invention are to provide a fireplace having a fire-well in the bottom thereof with a hot-air chamber completely surrounding same together with another hot-air chamber enclosed by a radiator-plate and in communication with the first named chamber whereby the maximum amount of heat from the fire is utilized in heating the air that is drawn into the chambers and returned to the several rooms by pipes or conduits as hereinafter set forth. Other objects are to provide means for a direct fire draft and gravitational means for discharging the ashes from the fire.

With the above and other objects in view which will appear as the description proceeds, the invention consists of the novel construction, combination and arrangement hereinafter described and claimed. These objects are accomplished by devices illustrated in the accompanying drawings; wherein:

Figure 1 is a view partly in front elevation and partly in vertical section as determined by the broken line 1, 1 of Fig. 2;

Fig. 2 is a view in transverse vertical section taken substantially on a broken line 2, 2 of Fig. 1;

Fig. 3 is a view in horizontal section taken on a broken line 3, 3 of Fig. 2; and

Fig. 4 is a view in horizontal section taken on a broken line 4, 4 of Fig. 2.

Referring to the drawings throughout which like reference numerals designate like parts, the numerals 5 and 6 indicate respectively the floor and vertical wall of a room wherein the fireplace is located. Said fireplace has the usual opening 7 for the fire and a chimney flue 8 leading upwardly therefrom.

A fire-well 9 is disposed in the bottom of the opening 7 with its open top substantially flush with the flooring 5. Said fire-well has vertical upper side walls 10 and lower convergent side walls 11 with a grate 12 supported at their joinder substantially midway of the depth of said well. Said well has a restricted bottom 13 with an ash-chute 14 depending therefrom whereby the ashes from the grate will fall and be carried off by gravity as will be readily understood.

The back wall 10 of the fire-well 9 extends upwardly and is curved outwardly within the opening 7 in the form of a concave radiator plate 15. From a point 16 said radiator plate slants backwardly and upwardly, as at 17, to the rear chimney wall where its upper edge portion is set into the masonry as at 18. The lateral ends of said radiator plate at the floor or hearth level extend outwardly to form wings 19 whose ends are set into the side walls of the opening 7 as at 20. Thus a completely enclosed back-chamber 21 is formed by said radiator plate, walls, and flooring for reasons more fully hereinafter described.

A casing 22 is placed completely around the fire-well 9 in spaced relation thereto to form a bottom-chamber 23 extending all around said well. The upper edge of said casing is secured to the underside of the flooring 5 with the exception of its back wall which may be secured to the vertical wall 6 in any desired manner. It will be obvious that said bottom-chamber is sealed off with the exception of its back space which is in direct communication with the back-chamber 21 as clearly shown in Fig. 2 of the drawings.

The cool air is drawn into the bottom-chamber 23 by means of a pipe 24 which may have a plurality of other pipes connected therewith and leading to registers or openings in the several rooms of the house. The heat from the fire within the fire-well 9 will, of course, cause the warm air to rise into the back-chamber 21 where it is still subject to the heat from the fire striking against the radiator plate 15. From the upper end portion of said back-chamber the warm air will rise through openings 25 and pass through pipes 26 to registers 27 where it will be thrown out into the different rooms to replace the cool air which has been drawn therefrom, thus causing a continuous circulation.

For the purpose of providing ample draft for the fire within the fire-well 9 I have installed draft pipes 28 which may take cool air from points 29 within the room, such as registers or screened openings, and conduct same directly to the fire through a plurality of small openings 30 in the side walls of the well 9. The radiator plate 15 will project a certain amount of heat into the room and it will therefore be obvious that means is

provided for amply heating the room where-in the device is installed.

Thus it will be apparent that I have provided means for utilizing a maximum amount of heat generated by the fire within the open fireplace which is made to serve the economic purpose of heating the entire home and whereby the more expensive heating systems such as furnaces and the like may be eliminated.

Having thus described my invention what I claim and desire to secure by Letters Patent of the United States is:

1. A fireplace heating system comprising a fire-well, a radiator plate arranged to form a back-chamber, a casing arranged to form a bottom-chamber around the fire-well, and said bottom-chamber being in direct communication with said back-chamber.
2. A fireplace heating system comprising a fire-well, an upstanding radiator plate for said well arranged to form a back-chamber with the fireplace, a casing for the sides and

bottom of the well arranged to form a bottom-chamber therewith, said bottom-chamber in direct communication with said back-chamber, cool air conduits for the bottom-chamber, and warm air conduits for the back-chamber.

3. A fireplace heating system comprising a fire-well having convergent lower side walls, an ash-chute disposed in the restricted bottom of said well, draft conduits for the fire-well, a radiator plate for the well arranged to form a back-chamber with the fireplace, a casing for the sides and bottom of the well adapted to form a bottom-chamber therewith, said bottom chamber in direct communication with said back-chamber, cool air conduits for the bottom-chamber, and warm air conduits for the back-chamber.

In witness whereof, I hereunto subscribe my name this 21st day of February, A. D. 1928.

THOMAS BURLEY.
